UNITED STATES PATENT OFFICE.

LARS LARSSON, OF NEW YORK, N. Y.

FIRE-ESCAPE.

SPECIFICATION forming part of Letters Patent No. 650,403, dated May 29, 1900.

Application filed September 25, 1899. Serial No. 731,618. (No model.)

To all whom it may concern:

Be it known that I, LARS LARSSON, a citizen of the United States, residing at New York, in the State of New York, have invented a certain new and useful Fire-Escape, of which the following is a specification.

My invention has relation to fire-escapes, and more particularly to that class of fire-escapes in which a spring-motor is used by 10 which to return the belt or other lowering medium to the window or other opening to permit of the descent of other persons and in which a governor or brake is employed to govern the descent, the object of the invention being to generally improve such devices and to provide improved brake mechanism to automatically adjust the resistance, so that a heavy body will descend no faster than a light one.

20 My invention further consists of certain details of construction and combinations of parts, which will be hereinafter fully described, recited in the claims, and illustrated in the drawings, all forming a part of this 25 specification.

In the drawings, Figure 1 is a vertical sectional view of the invention on the plane indicated by the broken line 1 1 of Fig. 2 looking in the direction of the arrows. Fig. 2 is a vertical sectional view on a plane at right angles to that of Fig. 1, as indicated by the broken line 2 2 of Fig. 1, looking in the direction of the arrows. Fig. 3 is a vertical sectional view on a plane parallel to that of Fig. 1, as indicated by the broken line 3 3 of Fig. 2, looking in the direction of the arrows. Fig. 4 is a detail view, in front elevation, of the traveling guide-pulley removed from the casing. Fig. 5 is a detail vertical sectional view 30 illustrating the crank and adjacent mechanisms. Figs. 6 and 7 are detail vertical sectional views on planes indicated by the broken lines 6 6 and 7 7, respectively, of Fig. 5.

Like numerals of reference mark the same parts wherever they appear in the several figures of the drawings.

Referring to the drawings by numerals, 8 indicates the bottom of a box or casing 9, to be secured either within or without a window 50 or other opening in the wall, as may be desired, in this instance being illustrated as inside, the front or outer side being indicated

at 10 and the inner wall at 11. Within the casing are erected two uprights 12 13.

Journaled in suitable bearings in wall 10 55 and upright 13 is a shaft 14, to which one end of a coiled spring 15 is secured, the other end of the spring being secured to the casing. A gear-wheel 16 on shaft 14 meshes with a pinion 17 on a shaft 18, journaled in 60 uprights 13 and 12, on which shaft is secured a winding-drum 19. The opposite end of shaft 18 extends beyond upright 12, and on this extended end is secured, by means of a set-screw 20, a hub 21, having bifurcated 65 radial extensions 22 diametrically opposite each other. Journaled on this end of the shaft 18 is the head 23 of a crank-arm 24, said head being formed, as at 25 in Fig. 6, as a ratchet-wheel. Stop-pawls 27 28 are pivoted 70 in the bifurcated extensions 22 of hub 21 and are normally held in contact with the teeth of ratchet-wheel 25 by means of a spring 29, rotatably placed on shaft 18 and having wings 30 normally pressing the inner ends of the 75 pawls outward, as shown in Fig. 5.

In line with shaft 18 is a shaft 31, journaled in suitable bearings 32 on the inner wall of the casing and having a crank-arm 33. In the opposite faces of crank-arms 24 and 33 80 are journaled yokes 34 and 35, in which is slidably fixed a head 36, rigidly secured to the outer end of a piston-rod 37, which passes through the head of a cylinder 38, secured in the casing, and carries at its inner end a solid 85 piston 39. Communication between the ends of the cylinder on opposite sides of the piston is afforded by a pipe 40, in which is a valve 41 to regulate the flow.

42 indicates a lever pivotally attached at 90 the upper end of upright 13 and resting upon a spiral spring 43, coiled around upright 12 and supported on a shoulder 44 on said upright at the end of lever 42. It is connected by a link 45 with the arm or lever 46 of valve 95 41. Swung upon lever 42 is a pulley 47, arranged to swing freely, as shown best in Fig. 2. A pulley 48 is journaled in bearings secured to the bottom of the casing alongside of or adjacent to an opening therein.

Fixed in upright bearings or supports 49 and 50, secured to the bottom of the casing, are two rods 51 and 52, the former being plain and the latter threaded and both parallel with

the axis of the winding-drum. Upon the threaded rod 52 is mounted a pulley 53 with a corresponding interior thread and provided with annular grooves in its hub, in which engage the lower ends of plates 54, slidably mounted on the rod 51. These plates are joined at their upper ends by a block 55, which carries a rope-guide 56. A rope 57, preferably about a quarter-inch steel-wire cable, is secured at its inner end to the winding-drum and spirally wound thereon, as at 58, passed down under and around the pulley 53, thence up and over pulley 47, and thence down over pulley 48 and out through the 15 opening in the bottom of the casing, a belt 59, with hook 60 or any other suitable device for attachment for the person or thing to be lowered, being secured at its end and a ball 61 near its end, the ball being preferably covered with rubber and of a diameter slightly greater than that of the opening through which the rope passes.

The operation of my invention may be described as follows: The parts being adjusted 25 as set forth, a person desiring to descend will secure the belt 59 around the body, securing it by engaging the hook 60 around the cable, and step out of the window. The weight being greater than the capacity of the spring 15 30 to uphold it, it descends, unwinding the cable from the drum, causing the drum-shaft 18 to rotate and by means of the pawls 27 and 28 and ratchet-wheel 25 rotating the crank-arms 24 and 33 and yokes 34 and 35. This rotation of the yokes will cause the head 36, piston-rod 36^a, and piston 39 to reciprocate in cylinder 38. The rapidity of this reciprocation of the piston is regulated by the extent the valve 41 is opened, and this valve will be 40 regulated by the weight of the person or thing being lowered, the weight of the latter pulling down on lever 42, and thus through the medium of link 45 and lever 46 causing the valve to be partially closed when a greater 45 weight is suspended on the cable, and the spring 43 raising the lever 42 and partially opening the valve when the weight is light. When the limit of lowering is reached, the belt is released, and the spring 15 will cause 50 the shaft 18 to be turned in the opposite direction, again winding up the cable on the drum, the pawls 27 and 28 slipping over ratchet-wheel 25 during the rewinding.

During the winding or unwinding of the 55 cable on the drum the pulley 53, being rotated

by the passage of the cable over it, will be caused to move longitudinally on the threaded rod 52, thus guiding the cable, so that it will be evenly wound upon or unwound from the drum, thus preventing irregularity in the 60 winding, which would interfere with the regularity of the descent.

When the cable is wound up by the action of spring 15, the ball 61 will serve as a stop to prevent the cable from being drawn into 65 the casing and as a stopper to close the opening to prevent the entrance of dampness, dust, &c.

The advantages attending the use of my invention will be obvious from the foregoing 70 description of its construction and operation and need not be further enlarged upon.

Having thus fully described my invention, what I claim as new, and desire to obtain by Letters Patent of the United States, is—

1. In a fire-escape, the combination with a drum, a shaft therefor, crank-arms upon the shaft, yokes journaled in the ends of the crank-arms, a head slidably mounted in said yokes, a piston-rod secured to the head, a cylinder, 80 a pipe, connecting its opposite ends, a valve in the connecting-pipe, a lever thereon, a lever connected to said valve, and a pulley on the lever over which the cable from the drum is passed, substantially as described.

2. In a fire-escape, the combination with a winding-drum, of a cylinder, a piston therein connected to and operated by the drum-shaft, a regulating-valve, a pulley over which the cable passes from the drum, a spring-supported lever carrying said pulley and connections between the lever and the valve, whereby the extent of its opening is governed by the weight of the cable being lowered to regulate the speed of the descent, substantially as de- 95 scribed.

3. In a fire-escape, the combination with a winding-drum of a plain guide-rod and a threaded rod fixed in parallelism with the drum-shaft, a pulley threaded upon the threaded rod having hubs with annular grooves, plates in said grooves engaging the guide-rod, a block connecting the plates, and a thread-guide on the block, substantially as described.

LARS LARSSON.
